UNITED STATES PATENT OFFICE.

FREDRICK C. LUETHY, OF STOUGHTON, WISCONSIN.

STREET-INDICATOR.

1,142,718.

Specification of Letters Patent.

Patented June 8, 1915.

Application filed June 17, 1914. Serial No. 845,680.

To all whom it may concern:

Be it known that I, FREDRICK C. LUETHY, a citizen of the United States, residing at Stoughton, in the county of Dane and State of Wisconsin, have invented a new and useful Street-Indicator, of which the following is a specification.

The device forming the subject matter of this application is adapted to be employed for indicating to the occupants of a railway car or other vehicle, intersecting streets, stations and other points at which passengers may desire to alight.

The present invention aims to provide novel means whereby the indicator may be operated from the trolley wire.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—Figure 1 is a sectional view depicting a portion of a car equipped with the device constituting the subject matter of this invention, parts appearing in elevation; Fig. 2 is a section on the line 2—2 of Fig. 1; Fig. 3 is a cross section showing the slide and its mounting; Fig. 4 is an elevation depicting the upper end of the trolley pole and attendant parts.

In the accompanying drawings, the numeral 1 indicates the roof of a car, the ceiling being denoted by the numeral 2 and being provided with an opening 3.

Mounted on the roof 1 or otherwise disposed is a support 4 to which a primary lever 5 is pivoted as shown at 6, one end of the lever 5 terminating in a hook 7 engaged with the flexible element 8 passed around a guide sheave 9 carried by the roof 1 and extended around a guide sheave 10 carried by the ceiling 2, the flexible element 8 being connected with a movable element 11 constituting a part of an indicator 12 of any standard construction.

Pivoted as indicated at 14 to the hooked end of the lever 5 is an arm 15 terminated

at its upper end in bifurcations 16 connected by a pin 17 receiving a hook 18 formed upon the lower end of a slide 19 mounted to reciprocate in a guide 20 secured to the trolley pole 21, the same being mounted as indicated at 22 upon the roof 1 of the car in any conventional or desired manner.

Connected as indicated at 23 with the slide 19 is a flexible element 24 passing through a guide 25 on the trolley pole 21, the upper end of the flexible element 24 being secured as indicated at 26 to one end of a curved segment 27 formed at the lower portion of a yoke 28, the segment being grooved to receive the flexible element 24 and the yoke being pivoted upon the axle 29 mounted in the upper end of the trolley pole 21 and carrying a trolley wheel 30 adapted to coöperate with a conductor 31 supported upon a bracket 32 of usual construction and held in place by the usual lateral guy wires 33.

Depending from the bracket 32 and held thereon by bolts 34 or the like are arms 35 supporting an auxiliary track 36 which is arched uprightly in its central portion, the auxiliary track 36 being adapted to be traversed by a wheel 37 journaled upon the yoke 28 adjacent the lower end thereof.

In practical operation, the wheel 37 rides up the track 36 to the apex thereof and is eased down the track 36, without objectionable noise. As the wheel 37 approaches the apex of the track 36, the yoke 28 is tilted on the axle 29 and the flexible element 24 is drawn upon, the same riding in the groove of the curved segment 27. When the flexible element 24 is drawn upon, the slide 19 will move in the guide 20, the hook 18 of the guide engaging the cross pin 17 of the arm 15 and elevating the arm, the arm 15 swinging the primary lever 5 upwardly on its fulcrum 6 and imparting a pull to the flexible element 8 through the instrumentality of the hook 7, the flexible element 8 passing over the sheaves 9 and 10, exerting a pull upon the movable element 11 and operating the indicator 12 at the appropriate time, to indicate the street, station or other point which is being approached. Owing to the presence of the pin 17, the trolley pole 21 may have the proper lateral movement when the car is turning the corner or rounding a curve. Since the arm 15 is pivoted as shown at 14 to the lever 5, the device will operate satisfactorily irrespective of the angle de-

fined by the axis of the trolley pole 21 and the horizontal.

Having thus described the invention, what is claimed is:—

- 5 1. In a device of the class described, a supporting structure; a lever fulcrumed at one end upon the supporting structure; an indicator; means for operatively connecting the indicator with the other end of the lever; an arm pivoted to said other end of the lever; a trolley pole mounted on the supporting structure; slidable means on the trolley pole coöperating with the arm; and mechanism for actuating the slidable means.
- 10 2. In a device of the class described, a car; direction changing idlers mounted on the car; an indicator on the car; a flexible element engaging adjacent edges of the idlers and operatively connected with the indicator; a lever fulcrumed at one end upon the car and at its other end connected with the flexible element; an arm pivoted to said other end of the lever; a trolley pole mounted on the car; slidable means on the trolley pole and engaged with the arm; and mechanism for actuating the slidable means.
- 15 3. In a device of the class described, a supporting structure; a lever fulcrumed at one

end upon the supporting structure; an indicator; means for operatively connecting the indicator with the other end of the lever; an arm pivoted to said other end of the lever and provided at its upper end with bifurcations; a connection between the bifurcations; a trolley pole carried by the supporting structure; a slide mounted to reciprocate in the trolley pole and engaged with the connection; and means for actuating the slide.

4. In a device of the class described, a car; an indicator thereon; a trolley pole on the car; a relatively fixed auxiliary track arched upwardly intermediate its ends; a yoke pivotally supported by the trolley pole; means for operatively connecting the yoke with the indicator; and means carried by the yoke for engaging the upper edge of the auxiliary track, thereby to effect a tilting of the yoke and to support the upper end of the pole against downward movement.

In testimony that I claim the foregoing as my own, I have hereto affixed my signature in the presence of two witnesses.

FREDRICK C. LUETHY.
